UNITED STATES PATENT OFFICE.

ADOLF A. STEINHILBER, OF ROCK ISLAND, ILLINOIS, ASSIGNOR TO ARTISTA PIANO
PLAYER COMPANY, OF MILAN, ILLINOIS, A CORPORATION OF ILLINOIS.

TREADLE FOR PIANO-PLAYING ATTACHMENTS.

1,136,733.

Specification of Letters Patent. Patented Apr. 20, 1915.

Application filed August 10, 1911. Serial No. 643,291.

To all whom it may concern:

Be it known that I, ADOLF A. STEINHILBER, a citizen of the United States, residing at Rock Island, in the county of Rock Island 5 and State of Illinois, have invented certain new and useful Improvements in Treadles for Piano-Playing Attachments, of which the following is a specification.

This invention relates to improvements 10 in treadles, and more particularly folding treadles, for piano playing attachments, and one of the objects of the invention is to provide an improved device of this class, by which substantially uniform power may be 15 applied throughout, not only the entire range of movement of the treadles and the pumbers, but at any point in their range of movement, and by which a quick, positive return of the treadles to normal position will 20 be insured.

A further object is to provide an improved device of this class which will be simple, durable, and cheap in construction, and effective and efficient in operation.

25 To the attainment of these ends and the accomplishment of other new and useful objects, as will appear, the invention consists in the features of novelty in substantially the construction, combination and arrangement of the several parts hereinafter 30 more fully described and claimed, and shown in the accompanying drawings exemplifying the invention, and in which—

Figure 1 is a detail elevation of the base 35 of a musical instrument having a treadle attachment applied thereto, constructed in accordance with the principles of this invention. Fig. 2 is a detail end elevation partly in section showing the treadle attachment folded into the casing of the instrument. Fig. 3 is a view similar to Fig. 2, showing the treadle in position for use. Fig. 4 is an enlarged detail top plan view, partly in section, showing the treadle in position for use. 45 Fig. 5 is a sectional view on line 5—5, Fig. 4. Fig. 6 is a detail perspective view of a portion of one of the links which connects the treadle with the operating shaft. Fig. 7 is a detail view partly in elevation and 50 partly in section of another manner of connecting the crank arm with the bellows.

Referring more particularly to the drawings and in the present exemplification of the invention, the numeral 10 designates a 55 portion of the instrument to which this im-

proved attachment is applied, and the casing is provided with an open front adjacent the bottom. Within this casing, and preferably adjacent each side thereof and remote from the extremity 11 of the strings, 60 which latter extend into the base, and so as not to form an obstruction in front of the strings, are located two pumbers or suction creating devices 12, in the form of pneumatics or bellows. Each of these bellows 65 12 is secured in position in any suitable manner, preferably by means of supports 13, to which one of the members of the bellows is secured, preferably the front member, and the bellows 12 are arranged so that the 70 movable member thereof will be disposed across the rear of the instrument and in a position to swing in an upright plane.

An elastic member 14 is arranged between the movable member 15 of the bellows 75 and the rear wall 16 of the casing, which elastic member tends normally to collapse the bellows. Suitably spaced bearings 17 are provided, and are arranged in pairs, and journaled in the respective pairs of 80 bearings are shafts 18, one of which shafts is provided for each of the bellows or pumbers 12. These shafts are spaced longitudinally from each other, and connected to each of the shafts adjacent one extremity 85 thereof are crank arms 19, each of which preferably carries an anti-friction roller 20, adapted to engage a projection 21 carried by the movable member 15 of the bellows. Secured to each of the shafts 18 adjacent the 90 other extremity thereof is another crank arm 22, similar to the crank arms 19, and are arranged in line with the latter and in such positions that they are adapted to be connected to the treadles 23 in a manner to be 95 hereinafter set forth, so that when the treadles are operated, the shafts 18 will be rocked in a direction to cause the anti-friction roller 20 to ride against the projection 21, and move the movable member 15 100 of the bellows in a direction to expand the bellows against the tension of the elastic members 14.

The treadles 23 are supported by spaced 105 parallel members 24, one extremity of each of which is deflected as at 25 to form a journal, journaled in bearings 26 secured to any fixed part of the casing. These members 24 project through the opening in the case and are of any desired length, the free 110

extremities thereof being connected by means of a cross bar or rod 27 (see particularly Fig. 4). Supports or feet 28 are provided, and are connected with the cross rod 27, and serve as a means for supporting the forward or free ends of the members 24. These members 24 are preferably arched as at 29 (see Figs. 2 and 3), so as to extend over the toe rail 30 of the casing when the 10 treadles are in position for use, and so as to allow the feet or support 28 to engage and rest upon the floor. The treadles 23 are pivotally connected as at 31 adjacent their forward edges to the cross bar 27, and 15 about which the treadles are adapted to be rocked. A link 32 (see particularly Fig. 6) is pivotally connected by one extremity 33 to the edge of the treadle adjacent their rear ends, and this link is pivotally connected adjacent its other end as at 34 to the crank arms 22 of the respective shafts 18. The link 32 is arched as at 35 between its ends, so as to arch over the toe rail 30 to permit the treadles to be freely 20 operated and to prevent the link from engaging the toe rail. If desired the toe rail may be provided with a recess or opening 36, within which a portion of the link 32 may operate. Pivotally connected to each 25 of the links 32 at a point adjacent the point of pivotal connection of the link with the crank arm 22, and as at 37, is an extension member 38, conveniently constructed of two members secured together as shown more 30 clearly in Fig. 4, and the ends 39 of this member are separated to form a shoulder 40. The extremity 41 of the link 32 is shouldered as at 42, and this portion 41 projects into the space between the members 39 to 35 coöperate with the shoulder 40 of the extension 38, to form a "rule joint," that is, a joint which will permit the extension and link to be folded with respect to each other in one direction and to lock them against 40 folding in the opposite direction. The other end of the extension 38 may be similarly formed, and an anti-friction roller 43 may be provided, which is journaled to the free end of the extension. The rollered ends 45 of the extensions 38 are adapted to enter and move along the guideway 48, which is preferably formed in the base of a support 45, to be hereinafter explained. The top and bottom 49 and 50 are spaced apart sufficiently to substantially prevent any vertical movement of the rollered ends of the extensions 38, but they allow the rollered ends of the extensions to freely move horizontally. This arrangement of the parts constitutes shifting fulcrums for the ends of the extensions 38, as will hereinafter appear. It is thought that since the two sets of levers 32 and extensions 38 are identical, a description of the operation of one of them will be 55 sufficient.

Referring more particularly to Fig. 3, the lever 32 and its extension 38 constitute what I term for convenience of description a "rule joint" or a "combination lever". The rule joint action is provided merely for the purpose of permitting the parts to be compactly folded up, but so far as the operation of the lever 32 and its extension 38 are concerned, when the treadles are swung outwardly in operative position, the member 32 and extension 38, forming the combination lever, will act as though they were rigidly connected together, and may therefore be regarded as a single continuous piece, and in the following description this should be kept in mind. It will now be seen that when the treadle 23 is depressed, the point 33 necessarily moves in an arc which is in general almost vertically disposed. The treadle 23 and the member 35 act in a sense like a toggle, and the result would be that the crank 22 will be given a rotary movement about the axis of the shaft 18 and, through the medium of the shaft 18, will impart this movement to the pumbers 12, as before explained. It will be noted, however, that the pivotal connecting point 34 of the member 32 and the crank 22, moves in an arc which in general is disposed horizontally and in consequence when the point 33, during the depression of the treadle, reaches and passes a straight line drawn through the pivotal points 27 and 34, no further rotation in the same direction will be imparted to the crank 22, even though the depression of the treadle 100 23 is continued farther. In such position of the parts, however, the pumbers are only partially expanded. Since the member 32 and the extension 38 are rigid, any depression of the treadle will naturally cause the rollered end 43 to rise vertically, but before it rises any substantial amount it enters the guideway 48 and is confined thereby against vertical movement. The consequence is that the rollered end 43 becomes a shiftable fulcrum for the combination lever. Hence, the combination lever now becomes a lever of the second order, the rollered end 43 being the fulcrum, the pivotal point 34 being the point at which the load is connected and the point 33 being the point at which the power is applied. Therefore, a continued depression of the treadle will continue the rotation of the crank 22, and through the medium of the shaft, as before explained, will fully expand the pumbers. The purpose in arranging the rollered end 43 and the guideway 48 so as to form a shifting fulcrum, is obvious, since the point 34 necessarily moves in an arc. It is thus manifest that pressure 120 upon the treadle is substantially uniformly effective on the pumbers throughout the entire range of movement, as well as at any point in their range of movement. This mechanism also has another important func- 125 130

tion,—that of returning the treadles quickly and positively to their normal position, ready for another stroke. After the fulcrum of the combination lever has shifted, so to speak, from the point 34 to the rollered end of the extension 38, this rigid combination lever and the treadles form in a sense an extended toggle, the fixed pivotal point of which is at 27 and the movable or shiftable point of which is at 43. When the treadles are pressed all of the way down, the pivotal point 33 passes below a straight line drawn through the two extensions 27 and 43 of this extended toggle, and the tendency would ordinarily be for the treadles to lock in this position. It will be remembered that the pumbers are expanded against the tension of springs 14, which is intended to return the pumbers to their closed position when the pressure on the treadles is relieved. The springs, however, would not be effective to return the treadles to normal position if it were not for the fact that the rollered end 43 of the combination lever is confined against vertical movement and hence forms the fulcrum for the lever. The springs 14, acting through the crank 19 and shaft 18, exert a force upon the crank 22 to rotate said crank 22 in the reverse direction. Hence, the power for the return movement of the parts is applied at the pivotal point 34 when the pressure on the treadles is relieved. In other words, the combination lever now becomes a lever of the third order, with its fulcrum at 43, the weight at the treadle and the power being applied at the pivotal point 34 by the spring 14, and in consequence the treadles will be quickly and positively returned to their normal position.

The support 45 previously mentioned is provided in order to support the treadles 23 when folded into the casing, so as to hold them out of engagement with the strings. This support is comprised by the integral portions 50 and 49, which form the guideway 48, and by the upright portion which carries a cross bar or rest 46 at its upper end, the rest being preferably inclined forwardly, as shown in Fig. 2. This support is preferably arranged adjacent the rear wall of the casing, and in such position that when the treadles are folded into the casing the rear edge of the treadles will engage and rest upon the rest member 46. If desired, a cushion 47, of any suitable material, may be provided on the upper face of the rest member 46.

When the treadles are folded from the position shown in Fig. 3 to that shown in Fig. 2, the link or lever member 32 will swing about its point of pivotal connection 34 and will also fold with respect to the extension 38, the latter moving about its point of pivotal connection 37 with the link 32. When, however, the treadles are swung out-

wardly to operative position, the lever 32 and its extension form a rigid combination lever, as before explained. The treadle support and guideway, while shown in the present exemplification of the invention as formed in an integral structure, may be formed in any suitable or desired manner.

In the form shown in Fig. 7, an extension 52 is provided on the movable member of the bellows, which is preferably bifurcated at its free end as at 53, and a link 54 is pivotally connected by one extremity to the crank 19 and the free extremity of the link projects into the bifurcation of the extension 52, to which it is pivotally connected, as at 55.

What is claimed as new is:

1. In a folding treadle mechanism, the combination of a treadle support pivoted at its inner end to a stationary support, a rock shaft within the casing of the instrument, a bellows, an operative connection between the bellows and shaft, a treadle pivoted at its forward end to the treadle support, a crank on the shaft, a link connecting the free end of the treadle and the said crank, an extension member pivotally connected with the link to fold with respect to the link in one direction, during the folding movement of the treadle, and means for locking the link and extension against folding movement with respect to each other in the opposite direction when the treadle is unfolded.
2. In a folding treadle mechanism, the combination of a treadle support pivoted at its inner end to a stationary support, a rock shaft within the casing of the instrument, a bellows, an operative connection between the bellows and shaft, a treadle pivoted at its forward or outer end to the treadle support, a crank on the shaft, a link connecting the free end of the treadle and the said crank, an extension member pivotally connected at its outer end with the inner end of the link to fold with respect to the link in one direction during the folding movement of the treadle, interengaging means on the link and extension member for locking them against folding movement with respect to each other in the opposite direction when the treadle is unfolded.
3. In a folding treadle mechanism, the combination of a treadle support pivoted at its inner end to a stationary support, a rock shaft within the casing of the instrument, a bellows, an operative connection between the bellows and shaft, a treadle pivoted at its forward or outer end to the treadle support, a crank on the shaft, a link connecting the free end of the treadle and the said crank, and an extension member pivotally connected with the link to fold with respect to the link in one direction, during the folding movement of the treadle, and means for locking the link and extension against folding movement with respect to each other in the opposite direction when the treadle is unfolded.

connected at its outer end with the inner end of the link to fold with respect to the link in one direction during the folding movement of the treadle, a portion of the link beyond its point of connection with the said crank abutting the said extension member for locking said member and link against folding with respect to each other in the opposite direction and while the treadle is being operated, the inner end of the extension member engaging and moving on a fixed surface in the casing and forming a fulcrum for the link and extension member.

4. In a folding treadle mechanism, the combination of a treadle support pivoted at its inner end to a stationary support, a rock shaft within the casing of the instrument, a bellows, an operative connection between the bellows and shaft, a treadle pivoted at its forward end to the treadle support, a crank on the shaft, a link connecting the free end of the treadle and the said crank, an extension member pivotally connected with the link to fold with respect to the link in one direction during the folding movement of the treadle, a position of the link beyond its point of connection with the said crank, abutting the said extension member for locking said member and link against folding with respect to each other in the opposite direction and while the treadle is being operated, the free end of the extension member engaging and moving on a fixed surface in the casing and forming a fulcrum for the link and extension member, and a support within the casing upon which the treadle rests when folded into the casing, and a combined guide and support within the casing into which guide the free end of the extension member is movable and upon which support the treadle rests when the latter is folded into the casing.

5. In a folding treadle mechanism, the combination of a treadle support pivoted at its inner end to a stationary support, a rock shaft within the casing of the instrument, a bellows, an operative connection between the bellows and shaft, a treadle pivoted at its forward end to the treadle support, a crank on the shaft, a link connecting the free end of the treadle and the said crank, an extension member pivotally connected with the link to fold with respect to the link in one direction during the folding movement of the treadle, a position of the link beyond its point of connection with the said crank, abutting the said extension member for locking said member and link against folding with respect to each other in the opposite direction and while the treadle is being operated, the free end of the extension member engaging and moving on a fixed surface in the casing and forming a fulcrum for the link and extension member, and a support within the casing upon which the treadle rests when folded into the casing.

6. In a folding treadle mechanism, the combination of a treadle support pivoted at its inner end to a stationary support, a rock shaft within the casing of the instru-

ment, a bellows, an operative connection between the bellows and shaft, a treadle pivoted at its forward end to the treadle support, a crank on the shaft, a link connecting the free end of the treadle and the said crank, an extension member pivotally connected with the link to fold with respect to the link in one direction during the folding movement of the treadle, a position of the link beyond its point of connection with the said crank, abutting the said extension member for locking said member and link against folding with respect to each other in the opposite direction and while the treadle is being operated, the free end of the extension member engaging and moving on a fixed surface in the casing and forming a fulcrum for the link and extension member, and a support within the casing upon which the treadle rests when folded into the casing, and a combined guide and support within the casing into which guide the free end of the extension member is movable and upon which support the treadle rests when the latter is folded into the casing.

7. In a folding treadle mechanism, the combination of a treadle support pivoted at its inner end to a stationary support, a rock shaft within the casing, a bellows, an operative connection between the shaft and bellows, a treadle pivoted to the support, a link connecting the treadle with the rock shaft, said link and treadle support being arched to extend over the toe rail, and an extension member connected with the link and extending into the casing and adapted to fold with the link when the treadle is folded, the free end of the extension engaging and being movable on a fixed support, and inter-engaging means on the link and member for locking the member with respect to the link when the treadle is being operated to form a rigid extension of the link whereby the free end of the extension will form a fulcrum for the link and extension.

8. In a folding treadle mechanism, the combination of a treadle support pivoted at its inner end to a stationary support, a rock shaft within the casing, a bellows, an operative connection between the shaft and bellows, a treadle pivoted to the support, a link connecting the treadle with the rock shaft, said link and treadle support being arched to extend over the toe rail, and an extension member connected with the link and extending into the casing and adapted to fold with the link when the treadle is folded, the free end of the extension being movable, means for locking the member with respect to the link when the treadle is being operated to form a rigid lever, the free end of the extension forming a fulcrum therefor, and a guide way for the free end of the said extension member.

9. In a folding treadle mechanism, the

combination of a treadle support pivoted at its inner end to a stationary support, a rock shaft within the casing, a bellows, an operative connection between the shaft and bellows, a treadle pivoted to the support, a link connecting the treadle with the rock shaft, said link and treadle support being arched to extend over the toe rail, and an extension member connected with the link 5 and extending into the casing and adapted to fold with the link when the treadle is folded, the free end of the extension engaging and being movable on a fixed support, means for locking the member with respect to the link when the treadle is being operated to form a rigid extension of the link whereby the free end of the extension will form a fulcrum for the link and extension, and a support within the casing 10 for receiving and holding the treadle when the latter is folded into the casing.

10. In a folding mechanism, the combination of a treadle support pivoted at its inner end to a stationary support, a rock shaft 15 within the casing, a bellows, an operative connection between the shaft and bellows, a treadle pivoted to the support, a link connecting the treadle with the rock shaft, said link and treadle support being arched to 20 extend over the toe rail, and an extension member connected with the link and extending into the casing and adapted to fold with the link when the treadle is folded, means for locking the member with respect 25 to the link when the treadle is being operated to form therewith a rigid lever whereby the free end of the extension will form a fulcrum for the link and extension, and a combined treadle support and guide within 30 the casing for receiving and supporting the treadle when the latter is folded into the casing, and for guiding the free end of the 35 said extension members.

11. In a device for the purpose described,

Copies of this patent may be obtained for five cents each, by addressing the "Commissioner of Patents, Washington, D. C."

the combination of the treadle proper, a pivotal support therefor, a pumper, an oscillator arm for operating the pumper, a lever engaging said arm for imparting oscillating motion thereto, and operatively related at one end to the treadle proper for receiving motion therefrom and having an extension at its other end projecting beyond the point of engagement thereof with said arm; and means for restricting the arcuate direction of movement of the end of said extension about the said point of engagement as a center. 45

12. In a device for the purpose described, the combination of a treadle, a bellows, a jointed lever connected at one end to said treadle and having its other end restricted to a reciprocating movement, and means connected with said lever intermediate the ends thereof for operating said bellows. 50

13. In a device for the purpose described, the combination of a lever, a treadle pivotally connected to one end of said lever, means confining the other end of said lever to a reciprocating movement, a crank connected to said lever intermediate the ends 60 thereof, and a bellows operated by said crank. 65

14. In a device for the purpose described, the combination of a treadle, a lever pivotally connected to one end of said treadle, a bellows, means connected with said lever intermediate its ends for operating said bellows, and a guide for the free end of said lever confining it to a reciprocating movement. 75

In testimony whereof I have signed my name to this specification, in the presence of two subscribing witnesses, on this seventh day of August A. D. 1911.

ADOLF A. STEINHILBER.
